UNITED STATES PATENT OFFICE.

JOHN F. STEDMAN, OF TIGARD, OREGON.

TOOL-SUPPORTING STAND.

Application filed March 20, 1922. Serial No. 545,149.

To all whom it may concern:

Be it known that I, JOHN F. STEDMAN, a citizen of the United States, residing at Tigard, in the county of Washington and 5 State of Oregon, have invented certain new and useful Improvements in Tool-Supporting Stands, of which the following is a specification.

The stand which is the subject matter of 10 the present application for patent has been designed more particularly for supporting in operative position a manually guided and controlled power-driven band saw used by butchers, or any other tool which is to be 15 suspended from some overhead support.

The invention has for its object to provide a novel and improved portable stand of the kind stated, by the use of which the saw or other tool can be easily guided relative to 20 the work, and also to provide a counterbalance for the tool to facilitate the vertical adjustment thereof.

With the object stated in view, the invention consists in a combination and arrangement of parts to be hereinafter described and claimed, and in order that the same may be better understood, reference is had to the accompanying drawing, wherein:

Figure 1 is an elevation of the stand; Fig. 30 2 is an enlarged central vertical section thereof partly broken away, and Fig. 3 is a horizontal section on the line 3—3 of Fig. 2.

Referring specifically to the drawing, 5 35 denotes a standard rising to a suitable height from a base plate 6. The standard is tubular so that it may house a counterweight 7. The base plate has a top boss 8 into which the lower end of the standard is screwed, and 40 said plate is carried by a base frame consisting of a pair of parallel and laterally spaced angle bars 9 connected across at their ends by angle bars 10 extending outward from one side of the frame, and mounted on rollers 11 to facilitate transportation of the 45 stand, it being understood that the stand is portable.

To the upper end of the standard 5 is fastened an extension 12 of reduced diameter, the standard being thus made in two sections. The connection between the sections may be made by a screw joint as shown in Fig. 2. The section 12 is shouldered externally at the bottom, as shown at 13, which 55 is for a purpose to be presently described.

The standard section 12 pivotally supports

a bracket arm 14 extending outwardly and horizontally therefrom. The inner end of this bracket arm 14 has a hub 15 which fits rotatably on the standard section 12 so that the bracket arm may be freely swung in a horizontal direction. A thrust and radial bearing 16 is provided between the standard section 12 and the bracket arm hub 15, said bearing engaging the shoulder 13. At the top there is interposed between the standard section and the hub, a roller or other anti-friction bearing 16a. To prevent upward displacement of the bracket arm, there is screwed on the upper end of the standard 70 section 12, above the top of the hub 15, a cap 17. The standard section 12 is also tubular, and open at the top as well as at the bottom to permit the passage thereinto of a flexible cord, cable, chain or other suspension device 75 18, the same passing down into the standard section 5 and carrying at its lower end the counterweight 7.

The swinging bracket arm 14 carries guide pulleys 19 and 20 for the suspension line 18, the pulley 19 being located at the inner end of the arm to guide one end of the line downwardly into the standard sections 12 and 5, and the pulley 20 being located at the outer end of the arm to guide the other end of the line downwardly from the arm, this end carrying the saw or other tool 21.

The angle bars 10 of the base frame extend in the same general direction as the bracket arm 14 to impart the necessary 90 stability to the stand.

A means is also provided for limiting the swing of the bracket arm 14, the same being a lug or finger 22 depending from the bottom of the hub 15, and located between a pair of abutments 22a extending outwardly from the lower end of the standard section 12. These abutments may be screws, and the standard section 12 has a number of tapped holes so that the position of the 95 screws may be varied.

If the stand is to support a meat saw 21 as shown, it will be placed alongside a block 23 or other support for the meat to be operated on, so that the saw will be properly 105 located above said block.

In operation, the bracket arm 14 swings freely to follow the saw or other tool suspended therefrom by the line 18, and as the tool is counterbalanced it can be elevated 110 and lowered with but very little effort on the part of the operator.

I claim:

1. A tool supporting stand comprising a base, a stationary hollow standard rising from the base and having a hollow top extension which forms a bearing, a horizontal bracket arm having a hub at its inner end which is rotatably supported by the bearing, guide pulleys carried by the bracket arm, one of said pulleys being located above and at the outer end of the bracket arm, and the other above and at the hub, a flexible tool supporting line passing over the pulleys and having its ends depending therefrom, one end passing through the top extension of the standard and also into the standard, and the other end being adapted to support a tool, and a counterweight housed in the standard, said counterweight being attached to the first-mentioned end of the line.
2. A tool supporting stand comprising a base, a stationary hollow standard rising

from the base and open at its upper end, a bracket arm extending laterally from the upper end of the standard and pivotally supported thereby to swing in a horizontal direction, means for holding the bracket arm against movement on the standard in the direction of the length thereof, guide pulleys carried by the bracket arm, one of said pulleys being located above and at the outer end of the arm and the other above and at the inner end of the arm, a flexible tool supporting line passing over the pulleys and having its ends depending therefrom, one end passing into the standard, and the other end being adapted to support a tool, and a counterweight housed in the standard, said counterweight being attached to the first-mentioned end of the line.

In testimony whereof I affix my signature.

JOHN F. STEDMAN.
